CLAIM

The ornamental design for a display screen or portion thereof with graphical user interface, as shown and described.

DESCRIPTION

The FIGURE is a front view of a display screen or portion thereof with a graphical user interface, showing our new design thereof.

The outer broken lines in the FIGURE show a display screen or portion thereof, and form no part of the claimed design. The other broken lines in the FIGURE show portions of the graphical user interface, and form no part of the claimed design.

1 Claim, 1 Drawing Sheet

병용 주의

2021.12.27

같이 사용했을 때 부작용이 나타나거나 서로
호르몬이 감소하는 약을 병용 중입니다.

틀리미스 250mg

2021.12.22~2021.12.23

심바스트 20mg

2021.11.30~2021.12.30

이 두 가지 약을 같이 복용하는 경우, 고지했을 약의 부작용인 근육통, 근육 손상 등의 발생 가능성이 증가할 수 있어 같이 복용하는 것을 가능하지 못하시길 바랍니다.
